BOAT BAILING PUMP

Nolan K. Rhoades, Beloit, Wis., assignor to The Electric Storage Battery Company, Philadelphia, Pa., a corporation of New Jersey

Filed Aug. 6, 1962, Ser. No. 71,191

Term of patent 14 years

(Cl. D65—1)

FIG. 1 is a perspective view of a boat bailing pump showing my new design.

FIG. 2 is a side elevational view thereof.

FIG. 3 is a top plan view thereof.

FIG. 4 is a bottom plan view thereof.

FIG. 5 is an enlarged fragmentary top view.

The undisclosed side is substantially the same in appearance as the disclosed side.

I claim:

The ornamental design for a boat bailing pump, as shown and described.
